To all whom it may concern:

Be it known that I, Arthur H. Crapsey, Jr., a citizen of the United States of America, residing in Rochester, in the county of Monroe and State of New York, have invented a new, original, and ornamental Design for Slide Holding Box, of which the following is a specification, reference being had to the accompanying drawings, forming a part thereof, in which:

Fig. 1 is a perspective view of a slide holding box taken from the front and showing my new design;

Fig. 2 is a side elevation of the slide holding box shown in Fig. 1;

Fig. 3 is a rear elevation of the slide holding box shown in the preceding figures; and

Fig. 4 is a bottom plan view of the slide holding box shown in the preceding figures.

I claim:

The ornamental design for a slide holding box, as shown.
